(57) **CLAIM**

The ornamental design for a radio frequency identification device enclosure for shown and described.

DESCRIPTION

FIG. 1 is an isometric view of a radio frequency identification device enclosure according to an embodiment of the invention with elements in dashed lines forming no part of the claimed design.

FIG. 2 is a front view of a radio frequency identification device enclosure according to an embodiment of the invention with elements in dashed lines forming no part of the claimed design.

FIG. 3 is a back view of a radio frequency identification device enclosure according to an embodiment of the invention with elements in dashed lines forming no part of the claimed design.

FIG. 4 is a right side view of a radio frequency identification device enclosure according to an embodiment of the invention with elements in dashed lines forming no part of the claimed design. A left side view of a radio frequency identification device enclosure is an identical mirror image of FIG. 4 and is omitted.

FIG. 5 is a top view of a radio frequency identification device enclosure according to an embodiment of the invention with elements in dashed lines forming no part of the claimed design.

FIG. 6 is a bottom view of a radio frequency identification device enclosure according to an embodiment of the invention with elements in dashed lines forming no part of the claimed design.

FIG. 7 is an isometric view of a radio frequency identification device enclosure in a floor mounted environment according to an embodiment of the invention with elements in dashed lines forming no part of the claimed design.

FIG. 8 is an isometric view of two radio frequency identification device enclosures in a back-to-back, floor mounted environment according to an embodiment of the invention with elements in dashed lines forming no part of the claimed design.

FIG. 9 is an isometric view of a radio frequency identification device enclosure in a wall mounted environment according to an embodiment of the invention with elements in dashed lines forming no part of the claimed design.

FIG. 10 is an isometric view of a radio frequency identification device enclosure in a recessed, wall mounted environment according to an embodiment of the invention with elements in dashed lines forming no part of the claimed design.

FIG. 11 is an isometric view of a second embodiment of a radio frequency identification device enclosure according to an embodiment of the invention with elements in dashed lines forming no part of the claimed design.

FIG. 12 is a front view of a radio frequency identification device enclosure according to an embodiment of the invention with elements in dashed lines forming no part of the claimed design.

FIG. 13 is a back view of a radio frequency identification device enclosure according to an embodiment of the invention with elements in dashed lines forming no part of the claimed design.

FIG. 14 is a right side view of a radio frequency identification device enclosure according to an embodiment of the invention with elements in dashed lines forming no part of the claimed design. A left side view of a radio frequency identification device enclosure is an identical mirror image of FIG. 14 and is omitted.

FIG. 15 is a top view of a radio frequency identification device enclosure according to an embodiment of the invention with elements in dashed lines forming no part of the claimed design.

FIG. 16 is a bottom view of a radio frequency identification device enclosure according to an embodiment of the invention with elements in dashed lines forming no part of the claimed design.

FIG. 17 is an isometric view of a radio frequency identification device enclosure in a floor mounted environment according to an embodiment of the invention with elements in dashed lines forming no part of the claimed design.

FIG. 18 is an isometric view of two radio frequency identification device enclosures in a back-to-back, floor mounted environment according to an embodiment of the invention with elements in dashed lines forming no part of the claimed design.

FIG. 19 is an isometric view of a radio frequency identification device enclosure in a wall mounted environment according to an embodiment of the invention with elements in dashed lines forming no part of the claimed design; and,

FIG. 20 is an isometric view of a radio frequency identification device enclosure in a recessed, wall mounted environment according to an embodiment of the invention with elements in dashed lines forming no part of the claimed design.
